(57) **CLAIM**

The ornamental design for the foldable packing case with optional attachable cover, as shown and described.

DESCRIPTION

FIG. 1 is an illustrative top front perspective view of a foldable packing case with optional attachable cover according to my new design, wherein the packing case is shown open and with the optional cover unattached;

FIG. 2 is an illustrative top front perspective view of the design of FIG. 1 with the optional cover removed;

FIG. 3 is a perspective side view of the design of FIG. 2 shown in a collapsed state;

FIG. 4 is a bottom plan view of the design of FIG. 2;

FIG. 5 is a top plan view of the design of FIG. 2;

FIG. 6 is an illustrative top rear perspective view of the design of FIG. 1 with the optional cover attached and closed;

FIG. 7 is a side view of the design of FIG. 6; and,

FIG. 8 is an unfolded view of the foldable packing case with optional attachable cover.
